William W. Roberts, of Hartford, Conn.,
Letters Patent No 1624 dated Aug. 5, 1862,

The schedule referred to in these Letters Patent and making part of the same.

To all whom it may concern:

Be it known that I William W. Roberts of the
City and County of Hartford, and State of Connecticut, have invented a
new and original design or pattern for a burial casket; and I do hereby
that the following is a full and exact description of the same, reference

being had to the accompanying photographic views, in which the same letters indicate like parts.

In the accompanying photographic views is shown a new and original design for a burial casket. a, a', are sides and ends of the casket, having moulding panels b, configurated thereon c, are flattened corners of the sides and ends. d, is the lid proper, - e, is a raised panel, f, is a glass opening in the lid d, - g, is a cover for the glass, h, are mouldings which surround and embellish the panel d, and glass opening f.

The whole combined to produce a rich ornamental design or pattern for a burial casket.

What I claim and desire to secure by Letters Patent, is the general design or pattern substantially as represented in the accompanying illustrations and description.
